DOG COLLAR ORNAMENT OR SIMILAR ARTICLE

Daniel A. Klimkiewicz, Rutherford, N.J., assignor of one-half to Ronald A. Darby, Hawthorne, N.J.

Filed Sept. 23, 1965, Ser. No. 87,131

Term of patent 14 years

(Cl. D12—2)

FIG. 1

FIG. 2

FIGURE 3 is a left side elevational view of the dog collar ornament shown in FIGURE 1, the right hand side being a mirror image of the left hand side.

The fragmentary broken line portion of the drawing figures represent a partial showing of a dog collar for illustrative purposes only.

I claim:

The ornamental design for a dog collar ornament or similar article, as shown and described.
